UNITED STATES PATENT OFFICE.

WILLIAM WESLEY CROCKER, OF JUNCTION CITY, KANSAS.

CLOTHES STICK.

Application filed October 16, 1920. Serial No. 417,295.

To all whom it may concern:

Be it known that I, WILLIAM WESLEY CROCKER, a citizen of the United States, residing at Junction City, in the county of 5 Geary and State of Kansas, have invented a new and useful Clothes Stick, of which the following is a specification.

This invention relates to clothes sticks, and more particularly to a head employed 10 on one end of a clothes stick for assisting in removing wet clothes from a boiler, during the washing of the clothes.

The object of the invention is to provide a head of this character which will catch into 15 the clothes and wind the same around the head to insure against the clothes becoming displaced from the head.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

Figure 1 illustrates a side elevational 30 view of a head constructed in accordance with the present invention.

Figure 2 is a front elevational view of the same.

Figure 3 is an end elevational view of 35 the head.

Referring to the drawing in detail, the reference character 5 designates the socket member of the head which tapers toward the free end thereof to receive the tapered extremity of a clothes stick.

The head is formed preferably of metal

capable of being cast, so that the cost of production may be reduced to a minimum, and as shown, the head includes an enlargement 6 which is relatively flat, the edges 45 thereof tapering towards a central line to provide substantially pointed ends 7.

Formed integral with the enlargement 6 is an enlargement 8 which also has tapering ends 9 that extend in directions at right 50 angles to the enlargement 6 so that the head will have a double grip on the clothes with which the same contacts.

In the use of the device, a stick, which in the present showing is illustrated by the reference character 10, and on which is supported the head, is forced into a boiler of clothes, whereupon the stick is twisted causing the clothes to become wrapped around the head, where the same may be readily and 55 easily removed from the boiler, eliminating any possibility of the clothes becoming displaced from the head.

Having thus described the invention, what is claimed as new is:

A clothes stick including a head formed with a socket member, integral elongated lateral projections formed at the free end of the head, said projections being disposed adjacent to each other and having approximately flat side faces, the projections being disposed at right angles to each other and in staggered relation and tapered to the ends thereof.

In testimony that I claim the foregoing as 75 my own, I have hereto affixed my signature in the presence of two witnesses.

WILLIAM WESLEY CROCKER.

Witnesses:

A. A. THOMAS,
ALICE E. MICKEY.
